CASTER CUP OR SIMILAR ARTICLE

Betty Auer, Chicago, Ill.

Application September 27, 1950, Serial No. 12,366

Term of patent 14 years

(Cl. D10—6)

To all whom it may concern:

Be it known that I, Betty Auer, a citizen of the United States, residing at Chicago, in the county of Cook and State of Illinois, have invented a new, original, and ornamental Design for a Caster Cup or Similar Article, of which the following is a specification, reference being had to the accompanying drawings, forming a part thereof.

Fig. 1 is a top plan view of a caster cup or similar article, showing my new design;

Fig. 2 is an elevational edge view thereof; and

Fig. 3 is an elevational view as seen when looking at a corner thereof.

The bottom of the caster cup is flat.

I claim:

The ornamental design for a caster cup or similar article, as shown and described.

BETTY AUER.
